DISPENSER WITH FOLLOWER AND
VALVED OUTLET

Martin Berg, Brooklyn, N. Y.

Application January 17, 1944, Serial No. 518,541

3 Claims. (Cl. 222—387)

1

This invention relates to a dispenser for materials of different consistencies, and from which it may be dispensed with facility in desired quantity.

Different kinds of dispensers had been used before which mainly consisted of two cylinders one of which could be screwed into the other thereby pressing out the content through an orifice. These kinds of dispensers could not be used for all materials namely fluid, semi-fluid and such of thick consistency and besides that most of them had an open orifice which made it possible that the material dried out or got spoiled. Other dispensers have also been used which contained merely one cylinder and a plunger fitting in the cylinder was forced down by a screw and thereby pressing the material out through a steadily open orifice arranged near the upper end of the dispenser. Thus this kind of dispenser could be used only for a limited number of materials and the steadily open orifice dried out the material very quickly.

It is, therefore, the primary object of the present invention to provide a universal dispenser which can be used for material of all consistencies—that means for fluid, semi-fluid and even thick consistency.

A further object of the present invention is to provide a dispenser with an orifice which has means for airtight close-up of said orifice.

Still another object of the invention is to provide a universal device of the above character which is very economical in manufacture, strong and durable in construction and will efficiently perform the function for which the same is devised.

A still further object of the invention is to provide a dispenser with means for providing pressure in the cylinder upon the goods, which means work independently from the closing means of the orifice.

Yet another object of the invention is to provide a dispenser in which the pressure means make the closing means of the orifice still tighter.

Other objects of this invention will be apparent from the following description of the dispenser which is illustrated by way of example in the accompanying drawing, of which:

Figure 1 is a vertical section of the dispenser along line 1—1 of Figure 3;

Figure 2 is a vertical section of the dispenser along line 2—2 of Figure 3; and

Figure 3 is a plan view of the device.

The dispenser consists of a cylinder 1 with an orifice 2 at its bottom 3, which orifice 2 is con-

2

ically shaped in order to serve as a valve-seat and to receive the conically shaped end 4 of a rod 5 extending through the cover 6 of the cylinder 1 which cover 6 is screwed to the cylinder 1 by means of a thread 7 adapted on top of the outside of cylinder 1. The bottom 3 of cylinder 1 is equipped integrally with an annular ring 8 to provide a standing base for the dispenser. A piston 9 glides along the rod 5 up and down by arranging a center opening 10, which piston 9 is connected with two rods 11 extending through holes 12 of the cover 6 and closing bridge-like to one piece. The top of the bridge part of the rods 11 has one or two grooves 13 to provide a rest for the fingers when using the dispenser.

The cover 6 is equipped with a vertically extending forked part 14 the top of which is arranged as pivot 14' for a double armed lever 15 extending to the center of the dispenser. The arm 16 of lever 15 extending to the center of the dispenser ends in a slot 17 arranged near the top of the rod 5, whereas the arm 18 of lever 15 extending away from the center of the dispenser is flattened to provide a larger surface for the finger actuating the dispenser. A spring 19 is adapted on rod 5, one end of which spring 19 presses against the cover 6 and the other against a spring plate 20 fixedly arranged on the rod 5.

The outside of the orifice 2 of the bottom 2 30 can be equipped with threaded outer surface 21 and a cup 22 screwed on that orifice 2, thereby closing up the orifice for filling purposes only.

Depending on what kind of material the dispenser is to be filled with the filling can take place either through the orifice 2 or through the top by unscrewing the cover 6 from cylinder 1 and removing piston 9 and rod 5 with cone 4 from the cylinder 1. In the first way no use has to be made of the cup 22, whereas filling the second mentioned way the cup 22 has to be attached first, to be removed again, when the filling is completed and the cover 6 is screwed to cylinder 1 again. In this position the contact of the container alone will press the cone 4 of rod 5 on the seat 2 but can be supported by a spring 19 and this will be sufficient to close up the container entirely. When liquid or semi-liquid materials are used the piston 9 and the rods 11 seem not necessary at all. Since the orifice 50 is arranged at the bottom the material will just flow out by pressing down arm 18 of lever 15 against action of the spring 19, if any spring is provided. By releasing the pressure on arm 18 the spring 19 returns the cone 4 immediately on its seat and closes the cylinder 1 air tight. In

order to achieve this, a tightening ring can be provided in the cover 6 where the rod 5 extends to the outside.

Whereas it is possible to fill up the cylinder 1 with liquid or semi-liquid material through the orifice 2 of the bottom of the cylinder 1 by lifting the valve 4, the filling of the cylinder 1 with material of thick consistency takes place advantageously from the top, after removing the stem 5, the valve 4, the piston 9, and the cover 6. Since the orifice 2 is open after removal of the stem 5 with the valve 4 a special closing cup 22 is provided in order to close up the orifice 2 during the filling period, but which cup 22 can be removed after inserting again the valve 4. In this case the dispensing is achieved by taking two steps. The first step will be pressing down the piston 9 by pushing down the bridge part 13 of the rods 11 with one or two fingers, in this way raising the pressure to the material to be dispensed, and the second step will be then to press down the arm 18 of the lever, upon reaching sufficient pressure to the material, in order to open the orifice 2, thereby dispensing material of thickest consistency, which could not be dispensed at all or only with difficulty. The dispenser is constructed in such a way that no material can be released unwillingly. Due to the construction of the dispenser and of the cone 4 of the rod 5 in particular, the cone will be pressed quite more on its seat and closed up tighter when pressure is exerted on the piston before rod 5 with its cone is raised. Whereas dispensing material out of the cylinder always follows the raising of pressure inside the cylinder in the known dispenser, it is different with the present dispenser. Raising of pressure provides, according to the present invention, a tighter sealing of the container and dispensing of the material despite the rise of the pressure cannot be achieved without lifting the cone 4 of rod 5 from its seat against spring pressure.

While there is above described but one embodiment of the invention, it is possible to produce still other embodiments without departure from the inventive concept above disclosed and it is therefore desired that only such limitations shall be imposed on the appended claims as are stated therein.

What is claimed as new and desired to be secured by Letters Patent is:

1. In a device for dispensing material, the combination of a container for said material with a piston in said container, a valve, a valve seat on the inside of said container for receiving said

valve, means for axial movement of said piston independently from the movement of said valve, said piston being adapted to apply predetermined pressure to the material before lifting said valve, and manually actuated means for lifting said valve at predetermined pressure, said first and second means being operated single-handed for movement in the same direction.

2: In a device for dispensing material, the combination of a container for said material with a piston in said container, a valve, a valve seat on the inside of said container for receiving said valve, a stem carrying said valve for controlling the lifting of said valve, means for axial movement of said piston independently from the movement of said valve, said piston being adapted to apply predetermined pressure to the material before lifting said valve, and manually actuated means for lifting said valve at predetermined pressure, said first and second means being operated single-handed for movement in the same direction.

3. In a device for dispensing material, the combination of a container for said material with a piston in said container, a valve, a valve seat on the inside of said container for receiving said valve, a stem carrying said valve for controlling the lifting of said valve, at least two bars extending axially from the said container, one end of said bars being secured to the said piston and the other ends being bridgewise connected for effecting the axial movement of the said piston independently from the movement of the said valve, and manually actuated means for lifting of the said valve from its seat, said bars and said lifting means being operated single-handed for movement in the same direction.
